UNITED STATES PATENT OFFICE

IRVING G. SCOTT AND MAUD C. FOX, OF NEW YORK, N. Y.

DESIGN FOR A FLOWER STAND

Application filed February 20, 1931. Serial No. 38,757. Term of patent 3½ years.

To all whom it may concern:

Be it known that I, IRVING G. SCOTT, a citizen of the United States, residing at New York city, in the county of New York and State of New York, and I, MAUD C. FOX, a citizen of the United States, residing at New York city, in the county of New York and State of New York, have invented a new, original, and ornamental Design for a Flower Stand, of which the following is a specifica-

tion, reference being had to the accompanying drawing, forming part thereof.

Fig. 1 is a top view of flower stand showing our new design and

Fig. 2 is a front view thereof.

We claim:—

The ornamental design for a flower stand as shown.

IRVING G. SCOTT.
MAUD C. FOX.
